AUTOMOBILE DOOR LATCH

Albert A. Cripps, Detroit, Mich., assignor to Ternstedt Manufacturing Company, Detroit, Mich., a corporation of Michigan

Application April 26, 1937, Serial No. 138,870

7 Claims. (Cl. 292—164)

This invention relates to an automobile door latch.

During the past few years great strides have been made in eliminating noises incident to the operation of the automobile. For example, in operation the engine and the rear end are almost silent. This advance in silencing the operation of the automobile has made the driver and passenger much more conscious of the lesser noises which previously were drowned out.

With the advent of the steel body with its pressed sheet steel panels, the body in a sense constitutes a drum which readily vibrates at audio frequencies and serves as an excellent means for transmitting noises. For example, the door comprises an outer sheet steel panel as well as an inner sheet steel panel which serves as an excellent amplifier for any noises created in the opening and closing of the door and in particular those created by the operation of the door latch. For instance, in the closing of the door the spring projected latch bolt is retracted as it first rides up the inclined face of the striker and thereafter is projected into interengagement with the step of the striker. This gives rise to one or both of two noises. First, the bolt head upon being projected may strike or abut against the bottom of the striker which sets up a metallic noise that is transmitted throughout the body, or secondly, the projection of the bolt may be arrested by a suitable stop provided on the latch frame. This also will set up a metallic noise or click which is transmitted along the body and amplified by the body and door panels.

It is the object of this invention to obviate the above-mentioned noises caused by the latch in the opening and closing of the door and by the operation of the latch either when the door is closed or opened. More particularly this invention contemplates a latch which is silent in operation.

In the drawings:

Fig. 1 is an assembly view of the latch.

Fig. 2 is a section along the line 2—2 of Fig. 1.

Fig. 3 is a fragmentary view of the general assembly of the latch showing the position of the parts when the bolt is retracted.

Fig. 4 is a section on the line 4—4 of Fig. 3.

Fig. 5 is a fragmentary rear elevation of the latch as viewed from within the automobile body.

Fig. 6 is a section along the line 6—6 of Fig. 2.

Fig. 7 is a detail of the bolt bumper.

Referring more particularly to the drawings there is shown a latch identical with that shown in the Andersen-Bowlus Patent No. 2,039,873,

May 5, 1936. This latch comprises a latch frame 1, a sliding bolt 2, selvage plate 3, bolt spring 4 mounted on the bolt and having its free end acting against the lever 5 which is pivoted on the latch frame as at 6, outer rollback 7, a connector 8 pivoted to the lever 5 for optionally connecting the outer rollback to the bolt, and the shifter lever 9.

The bolt head 25 is slidably guided in the opening 10 in selvage plate 3 and is also slidably mounted on the frame by means of the pin 11 which is riveted to the latch frame 1 and engages the bolt 2 in the elongated slot 12. All these details of the latch are shown in the above-mentioned Andersen-Bowlus patent.

The force of the bolt spring 4 at all times tends to project the bolt. In Fig. 1 the bolt is shown in fully projected position. At this time it will be noted that the connector 8 has a slight clearance with the shoulder 13 of the bolt and that the forward end of the bolt tail 15 also clears and is spaced from the selvage plate as at 16. Thus in the projection of the bolt by the bolt spring none of the above-mentioned parts serve to arrest the projection of the bolt. This is done entirely by means of the lug 17 struck or bent out of the bolt tail which abuts against the bumper 18.

The bumper 18 can be made from any suitable resilient distortable or sound deadening material and preferably is a rubber block vulcanized on the support bracket 19. The support bracket 19 is set into the depression 20 in the latch frame 1 to which it is secured by the pin 11. The end of the bracket fits snugly in the opening 20 in the latch frame and thus is prevented from turning when it receives the impact of the bolt. It will also be noted that the bumper 18 is positioned on the center line of the bolt. This prevents any tendency of the bolt to twist or shift laterally when the impact of the projected bolt is taken up by the bumper.

The bolt head 25 is arranged to interengage with the usual and well known striker plate having the usual inclined wedge face terminating in a step behind which the bolt head seats when the door is closed. The striker as usual has two such seats one of which is the final latching seat and the other of which constitutes the safety catch. Such a conventional striker plate is shown, for example, in the Saunders Patent 1,924,806, August 29, 1933. The important thing is that the striker step is arranged sufficiently deep so that the bolt head does not bottom against the vertical face of the striker plate after snap-

ping behind the final step or seat in the striker. In other words, the striker plate itself does not arrest the projection of the bolt 2 by the bolt spring 4 because the bumper 18 and lug 17 are arranged to serve as the sole means for arresting the projecting of the bolt by the bolt spring. Therefore in operation no metallic sound is set up by the bolt because the rubber bumper 18 acts as an effective sound deadener. This is true regardless of whether the bolt is retracted and then projected either in the opening or closing of the door or while the door is open or closed.

I claim:

1. An automobile door latch comprising a latch frame, a latch bolt slidably mounted on the said frame for rectilinear sliding movement, a spring for projecting said latch bolt, cooperating stops carried by said latch frame and bolt on approximately the longitudinal center line of said bolt, one of said stops comprising a metal bracket fixed to one of said bolt and frame members, and a rubber block secured to said bracket, said stops being located one relative to the other whereby the said stops abut in the projecting of the latch bolt to serve as the sole means for arresting the projecting movement of said latch bolt without creating metallic noises.
2. An automobile door latch comprising a latch frame, a latch bolt slidably mounted on the said frame for rectilinear sliding movement, a spring for projecting said latch bolt, cooperating stops carried by said latch frame and bolt on approximately the longitudinal center line of said bolt, one of said stops comprising a metal bracket fixed to the latch frame and a rubber block vulcanized thereon said stops being located one relative to the other whereby the said stops abut in the projecting of the latch bolt to serve as the sole means for arresting the projecting movement of said latch bolt without creating metallic noises.
3. An automobile door latch comprising a latch frame, a projectable and retractable latch bolt mounted on the frame, a lug struck up from one of said members, a bracket secured to the other member and a block of elastic, distortable material fixed on said bracket in the path of said lug, the said lug and block of elastic, distortable material being positioned one relative to the other whereby they serve as the sole means for arresting the projecting movement of the said latch bolt.
4. An automobile door latch comprising a latch

frame, a projectable and retractable latch bolt, a lug struck up from one of said members, a bracket riveted to the other of said members, a block of elastic, distortable, non-metallic material secured to said bracket, the lug on the one member being positioned relative to the bracket and block of elastic, distortable material on the other member to abut each other in the projection of the bolt and serve as the sole means for arresting the projecting movement of the latch bolt.

5. An automobile door latch comprising a latch frame including a selvage plate, a bolt slidably mounted on the frame, an opening in the selvage plate through which the head of the bolt projects and in which the head of the bolt is guided, a pin secured to the latch frame, a slot in the tail of the bolt, the said pin slidably engaging the tail of the bolt in the said slot to guide the same, a bracket secured to the latch frame by the said pin, a block of rubber secured in place by the said bracket, a lug struck up from the tail of the said bolt positioned relative to said rubber block to abut the said rubber block and cooperate with the said rubber block to serve as the sole means for arresting the projecting movement of the latch bolt.

6. In a vehicle door latch having a case plate and a spring tensioned latch bolt movable relative to said case plate to and from latching position, said latch bolt having a slot elongate in the direction of movement thereof, a pin fixed to said plate and having a portion disposed in said slot for guiding said latch bolt, a stop plate carried by said pin, a stop member carried by said bolt and disposed rearwardly of said stop plate, and a cushioning element carried by one of said stop plate and stop member for limiting the movement of said latch bolt to latching position.

7. In a vehicle door latch having a case plate and a spring tensioned latch bolt movable relative to said case plate to and from latching position, said latch bolt having a slot elongate in the direction of movement thereof, a pin fixed to said plate and having a portion disposed in said slot for guiding said latch bolt, a stop plate carried by said pin, a buffer element carried by said stop plate, and an outwardly projecting flange on said bolt engageable with said buffer member upon movement of said latch bolt to latching position.

ALBERT A. CRIPPS.
